COMBINED CURTAIN AND SHADE BRACKET

Jose Borges Cabral, New Bedford, Mass.

Application June 4, 1942, Serial No. 445,783

1 Claim. (Cl. 248—259)

This invention relates to a combined curtain and shade bracket, and it consists in the constructions, arrangements and combinations herein described and claimed.

It is a particular object of the invention to provide a unitary bracket construction in a manner to support a shade roller and curtain rod and embodying means whereby the bracket may be secured to the framing of windows of varying widths, without the use of nails or similar fastening devices.

It is also an object of the invention to provide a bracket of the nature stated, in which the essential parts may be stamped from sheet metal and which may be readily assembled for use without the use of special tools.

Additional objects, advantages and features of invention will be apparent from the following description and accompanying drawing, wherein

Figure 1 is a plan view of a bracket as installed upon a window frame.

Figure 2 is an end view thereof.

Figure 3 is a top edge view of the bracket, detached.

Figure 4 is a cross section on the line 4—4 of Figure 1.

Figure 5 is a view similar to Figure 1, illustrating a modified form of the bracket.

Figure 6 is an end view thereof.

Attention is first invited to Figures 1 to 4 wherein there is shown a bracket 10 consisting of a section 11 and a section 12, the latter being adjustably engaged with the section 11 for accommodation of varying widths of window framing, as well as described in greater detail.

The section 11 is of elongated form and has opposed longitudinal flanges 13—13'. A slot 14 is formed medially of the section, positioned between the flanges, as clearly shown in Figure 1. The slot 14 is of a length less than the length of the section, and in the present instance is shown as approximately one-half of the length of the section 11. The flange 13' is divided or cut as at 15, and from the section 11 there is an integral right angular extension 16, the outer end of which is bent at a right angle defining a flange 17 of a height the same as the flanges 13—13', thus maintaining the section flush against a frame when installed thereon.

The extension 16 is formed with a pair of outwardly bent ears 18, one on each longitudinal edge, and each extension is formed with a nib 19 as customarily employed upon brackets for support of a curtain rod.

The section 11 is also formed at one end with a

right angular end member 20 terminating in suitable prongs 21.

The section 12 is a rectangular flat strip of a width slidably engaged between the flanges 13 and 13' and has an open-ended slot 22 adapted to register with the slot 14 when in assembled relation. The end of the strip opposite the open end of the slot 22 is bent at right angles, forming an end member 23, lying in a plane parallel to the end member 20, and is also formed with angularly disposed prongs 24.

From the construction thus far described, it will be apparent that the sections 11 and 12 are telescopically arranged within one another, so that they can be adjusted to differing widths of frames, and when so arranged upon the frame respective ends 20 and 23 may be given a light blow to cause the prongs 21 and 24 to penetrate the frame for support of the bracket.

To further secure the sections 11 and 12 and to also afford support of one end of a roller shade, indicated at 25, provision is made of a bracket 26. The bracket 26 embodies a base member 27 of a width slightly less than that of the section 11 and has a tongue 28 of a width freely engageable within the slots 14 and 27 but of such width as to maintain the base 27 against turning movements. The base 27 has an aperture 29 for reception of a bolt 29 of a length extending through the slots 14 and 22 and receives thereon a nut 30, for clamping the sections 11 and 12 together as well as securing the bracket 26 in a rigid manner. It will be apparent that the bracket 26 may be adjusted to different positions along the slots 14 and 22 so as to accommodate various lengths of shade rollers.

In Figures 5 and 6, a modified form of the bracket is shown constructed for attachment to horizontally extended frame portions. In this form the telescoping sections 11' and 12' are arranged vertically rather than transversely of the frame as in the first form and are connected together by means of a bolt 29' and nut 30'. The section 11' has ears 18' for securing of a curtain rod as previously explained, and also has a lateral extension 35. The extension 35 is longitudinally slotted as at 36 for slidable mounting of a shade bracket 26' similar to the bracket 26 first described. The outer end of the extension 35 is bent at right angles to define a flange 37 corresponding in depth to the flanges 38 of the section 11'. These flanges butt against the frame for spacing the assembled bracket suitably from the frame.

While I have shown and described preferred

forms of the device, this is by way of illustration only, and I consider as my own all such modifications in construction as fairly fall within the scope of the appended claim.

I claim:

A combined shade and curtain bracket comprising a pair of sections, one of the sections consisting of an elongated portion having inturned longitudinal flanges and a right angular extension upon one of the sides of the elongated portion, said extension having a flange at its end of a depth the same as the first named flanges, the flanges forming a footing for engaging a window frame, and said extension further having ear members for support of a curtain rod, said elongated

portion having a slot intermediate its length, the other of said sections being a flat strip member of a width to be slidably engaged between the longitudinal inturned flanges of the first

5 named section, the flat strip member having a slot aligned with the first slot, a shade bracket having an apertured base aligned with the slots of the sections, a threaded fastener engaged through the aperture and aligned slots whereby to secure the 10 bracket upon the sections and to further hold the sections in a desired adjusted position, and each of said sections having prong members arranged in opposed relation to each other for penetration of a window framing for support of the bracket.

15 JOSE BORGES CABRAL.
